UNITED STATES PATENT OFFICE.

ALVAN W. LIGHTBURNE, OF LIBERTY, MISSOURI.

FLYING-MACHINE.

1,325,696.

Specification of Letters Patent. Patented Dec. 23, 1919.

Application filed October 30, 1917. Serial No. 199,343.

To all whom it may concern:

Be it known that I, ALVAN W. LIGHTBURNE, a citizen of the United States, residing at Liberty, in the county of Clay, State 5 of Missouri, have invented certain new and useful Improvements in Flying-Machines, of which the following is a full and exact specification.

The present invention relates to aeronautics, and one of the objects in view is to provide a flying machine construction involving a novel and improved propelling means comprising revolving vanes operating about axes at each side of the machine, 10 with each vane also oscillating about an individual axis for varying its effective operative surface as its position changes during each revolution.

It is also an object to devise a construction 20 of this character in which means is provided for convenient adjustment of the operative relation of the several vanes for the purpose of regulating the normal lifting and propelling force of the same.

25 It is also sought to provide a propelling and lifting construction of the type described together with a centrally mounted propeller member with drive connections thereto having provision for reversing the motion of the latter propeller member.

Another object of the invention is to provide a novel arrangement of elevating planes having means for operating the same in a manner adapted to afford a secondary 35 rudder action for steering the movement of the machine; and a further object is to devise an improved arrangement of connections for controlling the action of the main rudder member of the machine.

40 With these principal objects in view as well as minor objects as will appear in the course of the detailed description, the invention will now be described with reference to the accompanying drawings illustrating one form of construction which has been devised for embodying the improvements, after which those features and combinations deemed to be novel will be set forth and particularly defined in the appended claims.

In the drawings—

Figure 1 is a side elevation of a machine constructed in accordance with the present invention;

55 Fig. 2 is a plan view of the same with

parts of the rear planes slightly broken away to show the rear elevating planes;

Fig. 3 is a front elevation of the machine;

Fig. 4 is a section on the line 4—4 of

60

Fig. 1;

Fig. 5 is a section taken on the line 5—5 of Fig. 4;

65

Fig. 6 is an enlarged broken sectional view illustrating the manner of mounting the revolving vanes together with the cam means for oscillating the same;

Fig. 7 is a section taken on the line 7—7 of Fig. 6.

70

Fig. 8 is an enlarged detail view illustrating one of the cam members in relation to one of the flying vanes, the dotted lines representing the changed position of the vane as it traverses the cam-way;

75

Fig. 9 is an enlarged developed plan view of the cam member;

Fig. 10 is a section taken on the line 10—10 of Fig. 3, on an enlarged scale;

80

Fig. 11 is an enlarged sectional view of a clutch mechanism hereinafter described;

85

Fig. 12 is an enlarged detail elevation of the clutch element and shifter.

Referring to the drawings in detail, the framework or fuselage of the machine is designated generally by the numeral 14. 90 Carried at each of the opposite sides of said framework 14 is a normally fixed shaft 16 extending longitudinally of the machine and designed for the support of the plurality of revolving vanes 18 which are arranged in sets of preferably four in number, extending radially outward from the shaft and ninety degrees apart. The vanes are mounted upon the shaft by means of sectional bearing housings 20 secured together in alinement by bolts 22 and formed with bearings 24 for spindles 26 provided at the heads of the vanes 18. Each spindle 26 terminates in a crank 28 having a projection 30 for traveling in a cam groove 32 formed in a cam member 34, of which there is one to each set of vanes, said cam members being fixed to the shafts 16 and housed within the housing sections 20. The outline of each cam groove 32 is such as to maintain the vanes of each set with their planes at given angles to each other, preferably each vane being maintained at about 45 degrees angle to that at either side of it, and at right angles to the vane directly opposite,

95

110

on the other side of the shaft (see Fig. 7). Accordingly, with this arrangement, and with the vanes timed for bringing them into exactly horizontal position as they pass 5 downward through horizontal, they operate with maximum efficiency as regards lifting power; and as they pass upward through horizontal on the opposite or inner side of the shaft the vanes are then traveling with 10 the planes of the vane blades exactly vertical, with a minimum of resistance to the air,—it being understood that the vanes are so oscillated that in their intermediate positions they effect a combined lifting and 15 propelling action as said vanes are revolved about the shafts.

Means is also provided for regulating the position of the shafts 16 and said cam members 34 for varying the angle at which the 20 vanes 18 shall pass through horizontal. This regulating means comprises a segment 36 secured to one end of each shaft 16 adjacent to the framework 14, and a pin 38 actuated by a spring 40 into engagement 25 with any one of the openings 42 of said segment, the pins 38 being mounted in brackets 44 fixed to said framework (see Figs. 3 and 10). By swinging the segments laterally and thereby partially rotating the shafts 30 and the cam members 34, and securing the segments in adjusted position by means of the pins 38, it will be seen that the revolution of the vanes may be so timed as to bring them into horizontal position with 35 the planes of the vane blades at more or less of an angle to the horizontal, with the result that a proportionately lessened area of the vanes is operative for lifting as they pass through horizontal.

40 In the construction shown by the drawings, the vanes are arranged in two groups on each of the shafts 16, each group being provided with separate driving means consisting of chains 50 operating over sprocket 45 wheels 52 secured to the sectional housings 20. The chains 50 are also carried over driving sprocket wheels 54 mounted in pairs, one pair upon a short shaft 56 and the other pair upon a shaft 58 extending 50 parallel to the shaft 56 and in line with the shaft 60 of an engine 62 carried within the framework 14, the shaft 58 being operatively connected to said engine shaft and also connected with the shaft 56 through 55 gears 64 and 66. By this means the shafts 56 and 58 are driven in opposite directions for driving the shafts 16 also in opposite directions in the manner necessary for actuating the flying vanes downward through 60 their paths outside the frame 14.

A tubular propeller shaft 68 is also adapted to be driven from the shaft 58, the said shaft 68 being carried by the framework 14 in line with the shaft 58 and fitting 65 over the end of the latter (see Fig. 11), and

the front end of the shaft 68 carries a rotating propeller member 70 slightly in advance of the foremost set of flying vanes 18. The shafts 58 and 68 are operatively connected within a gear cage 72, where a clutch 70 element 74 is keyed slidingly upon the shaft 68 and adapted to be shifted into engagement with either a gear 76 secured to the shaft 58 or with a gear 80 loosely mounted on the shaft 68. Obviously if the clutch 75 element 74 is clutched with the gear 76 the shaft 68 will be driven directly and in the same direction as the shaft 58, but if clutched with the gear 80 it will be driven in the opposite direction through the train 80 of reversing gears 82, 84 and 86 in a manner which will be readily understood, the gears 82 and 84 being mounted on the same shaft 88 with the gear 82 in mesh with the gear 76, and the gear 84 in mesh with the intermediate gear 86 carried by a stud 90 and in its turn meshing with the gear 80. The clutch element 74 is shifted by means of a lever 92 pivoted at 94 to a bracket 96 and provided with spring elements 98 (see Fig. 90 12) for engagement with lugs 100 projecting from opposite sides of a yoke collar 102 carried by the clutch element 74, whereby the latter is yieldingly actuated into its clutching relation with either of the gears 76 and 80. With this arrangement of drive, the propeller member 70 may be driven direct from the shaft 58 for imparting to said member 70 a normal forward-propelling movement; or said propeller member may be quickly stopped and also reversed by shifting of the lever 92 at any time that it may be desired to check or counteract the action of the flying vanes 18 and thus check the forward movement of the machine by means 105 of this construction.

Triangular planes 104 and 106 are carried by the framework and at the rear of the flying vanes 18, and similarly formed planes 108 and 110 are carried by said framework 110 at the front of the vanes 18 for acting as elevating planes. In the case of the planes 108 and 110, these are positioned side by side with their outer edges hinged to the framework as shown at 112 (see Figs. 1 and 2), and at their inner margins said planes are connected to rods 114 operated by levers 116 mounted on the framework 14 and working along rack segments 118. The connections 115 120 at the opposite ends of said rods 114 are of ball and socket form to permit the necessary angular movement of the rods, the operation of the levers serving to swing said planes independently about their hinge mountings and effecting a rudder-like action 125 as well as elevating action of the planes, as occasion may require.

Rear elevating planes 121 are also provided beneath the planes 104 and 106, respectively, the same being hinged at their 130

front margins to the framework 14 and provided with crank elements 123 connected by rods 125 to operating levers 127.

The usual type of main lateral steering 5 rudder 122 is provided at the rear of the machine and pivoted upon vertical shaft 129 having a worm gear 124 (see Figs. 1 and 4) secured to the lower end thereof. An 10 operating shaft 126 is carried longitudinally of the frame and provided at its rear end with a worm 128 in mesh with said gear 124. The opposite end of said shaft carries a bevel gear 130 in mesh with a similar gear 132 secured to the lower end of a steering 15 shaft 134. This provides a convenient and efficient operating means for controlling the rear rudder from the operator's seat 136—in which connection it may be mentioned that all the manual operating elements 20 are located in position for convenient manipulation from this point.

From the foregoing it will be apparent that a comparatively simple and efficient arrangement and construction have been 25 devised for carrying out the desired objects of the invention, the operation of which will be sufficiently clear from the above description without requiring an extended detail explanation. A brief summary, however, of the same may be given. The flying 30 vanes 18 are driven from the engine through the drive chains 50, the sets of vanes at the opposite sides of the machine being revolved in opposite directions, and the action 35 of the cam elements 34 is such as to oscillate said vanes and cause them to assume horizontal position as they pass downward through the horizontal plane intersecting the shaft 16, and to assume vertical position 40 as they pass upward through said plane at the opposite side of said shaft; and intermediate said positions the vanes are alternately oscillated back and forth to effect the proper propeller action, all of which 45 will be clearly understood by reference to Fig. 7 of the drawings. In case, however, it should be desired not to exert the full lifting force of said vanes as they pass through horizontal position, the desired result 50 may be obtained by simple adjustment of the pins 38 into the proper openings 42 of the segments 36, whereby the shaft 16 and cam elements 34 are partially rotated and the oscillation of the vanes timed to 55 bring the latter into planes coinciding with the shaft at some interval either earlier or later than that at which they pass through the horizontal. By this arrangement a simple and readily controlled and easily adjusted 60 construction is obtained for accomplishing these various functions. The pro-

peller member 70 may be operated normally from the engine through the shafts 58 and 68, or the drive thereto may be disconnected or quickly reversed at any time that it may 65 be desired to rapidly check the forward movement of the machine. It will be further understood that the planes 108 and 110 perform all the functions of elevating planes, and by the peculiar mounting of the 70 same and connections for shifting them they may be conveniently operated to exert a rudder action to a certain extent for controlling the steering movements of the machine.

75

While I have illustrated and described what is now thought to constitute the preferred form of embodiment of the improvements, the right is reserved to all such formal changes or modifications as may fairly 80 fall within the scope of the appended claims.

What I claim is:

1. In a flying machine, the combination of the frame, a shaft extending longitudinally at each side of said frame, a plurality 85 of revolving vanes carried by each of said shafts and arranged in sets with the vanes of each set extending in different radial positions with respect to the axes of said shafts, means for revolving said vanes about 90 the axes of said shafts, a cam member carried by said shafts for each of said sets of vanes and operating to severally oscillate said vanes about individual axes at right angles to and intersecting the axes of said 95 shafts, and means for simultaneously adjusting the cam members on each shaft for varying the angle at which said vanes pass through horizontal position.

2. A flying machine construction comprising a frame having a shaft extending longitudinally at each side thereof, a plurality of revolving vanes carried by each of said shafts and arranged in sets with the vanes of each set extending in different 105 radial positions with respect to the axes of said shafts, means for revolving said vanes about the axes of said shafts, cam members fixedly secured to each of said shafts, one of said cam members being associated with 110 each of said sets of vanes and operating to severally oscillate said vanes about individual axes at right angles to and intersecting the axes of said shafts, and means for rotatively adjusting each of said shafts for 115 simultaneously adjusting the corresponding cam members and thereby varying the angle at which said vanes pass through horizontal position.

In witness whereof I affix my signature. 120

ALVAN W. LIGHTBURNE.
